DESIGN FOR A DRESS ENSEMBLE

Benjamin Rifkin, New York, N. Y.

Application January 29, 1940, Serial No. 89,842

Term of patent 3½ years

To all whom it may concern:

Be it known that I, Benjamin Rifkin, a citizen of the United States, residing at New York, city, county, and State of New York, have invented a new, original, and ornamental Design for a Dress Ensemble, of which the following is a specification, reference being had to the accompanying drawing, forming part thereof, where-in—

Fig. 2 is a back view thereof;

Fig. 3 is a front view of the dress of my dress ensemble, and

Fig. 4 is a back view thereof.

I claim:

The ornamental design for a dress ensemble, substantially as shown.

BENJAMIN RIFKIN.
